UNITED STATES PATENT OFFICE

THOMAS POSS, OF ASTORIA, NEW YORK

MULTIUNIT MATTRESS

Application filed February 11, 1929. Serial No. 338,987.

This invention relates to a multi-unit mattress and its object is to provide units of a shape and size adapted to be laid side by side on a bed, or like piece of furniture.

5 A further object is the combination in each of the said units of a supporting frame, spring elements, and a padded top layer.

Another object is a means for holding the units closely together in their assembled 10 formation.

These and other objects and features of the invention will be fully set forth and described in the following specification and illustrated in the accompanying drawings, in 15 which:

Fig. 1 is a top view of a mattress unit.

Fig. 2 is a bottom view of same.

Fig. 3 is a vertical section on the line 3—3 of Figure 1.

20 Fig. 4 is the marginal top frame of the spring section of the mattress.

Fig. 5 illustrates three of the units assembled together and held in position by a base clamp.

25 Fig. 6 is an enlarged fragmentary side view of one end of the base clamp.

Fig. 7 is a top view of the elements seen in Figure 6.

Fig. 8 is a fragmentary view of a slidable 30 clamp member with latch attached thereto.

Referring now to Figures 1, 2, 3 and 4 of the drawings; the construction is as follows: A unit 10 is built upon a base frame 11 which is preferably of wood. Springs 12 are secured to this base frame and rest upon it and

upon cross strands 13 which are stretched across the said frame. These springs are tied together and also tied to the said strands. These strands may be of wire, or any other 40 suitable material, or may be of strap formation.

A marginal frame 14, preferably of wire, is laid over the top of the springs and has 45 cross strands thereon in similar formation to those of the bottom element. Canvas 15 is stretched over the top and sides and secured to the bottom frame. A covering 16 is secured over the top of the spring section, and an 50 outside cover 17 is secured over the top and

at the sides of the spring section as illustrated. Cotton, felt, hair or like material 18 is stuffed between the spring section and the top cover and the said cover is tied down at intervals as seen at 19. Stuffing is also 55 placed in the side portions as shown at 20. A bottom covering 21 is secured over the base of the unit.

Referring now to Figure 5; the units 10 are shown assembled side by side. Two or more 60 may be used as required. These may be held in position by clamps as that seen at 25 the construction of which is illustrated in Figures 6, 7 and 8 of the drawings. These clamps each comprise a cross element 26 which is perforated as seen at 27. To this is slidably attached the end members 28 which are slotted as at 29 and retained by the bolts as seen at 30. At the end of the slidable member a spring 31 is attached and this engages the 70 perforations of the element 26. A finger grip 32 is provided on the latch for pressing down to open the clamp.

When the units are placed in position, the end members of the clamps are pushed tightly against the sides as shown; and when it is desired to open the clamps, a unit is slightly lifted to give access to the latch element. Two, or more clamps may be used as desired. 75

The mattress as shown has many desirable 80 features and advantages such as ease of handling due to the small size and light weight of the units. It is also easy to brush off and clean and is very sanitary and of neat and attractive appearance.

Having thus described the invention, what 85 is claimed as new and desired to be secured by Letters Patent, is as follows:

In an article of the character described, an 90 assembly of mattress units adapted to be placed together, and a clamp element adapted to be used under the said units and to compress the same together, the said clamp element comprising a base member, slidable end members mounted thereon by means of slots 95 therein and supporting bolts which are secured to the said base member, vertical end portions on the said slidable members, perforations in the said base member, and latches 100

on the said slidable members adapted to engage the said perforations and to lock the clamps in position.

Signed at New York in the county of New York and State of New York this 9th day of February, A. D. 1929.
